(57) **CLAIM**

The ornamental design for a knob for an aircraft center stick as shown and described.

DESCRIPTION

FIG. 1 is a front, right-side, and top perspective view of a knob for an aircraft center stick showing our new design; FIG. 2 is a rear, right-side, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right-side and top perspective view thereof, shown in a condition of use.

The dashed broken lines depict portions of the knob for an aircraft center stick that form no part of the claimed design. The dashed broken lines in FIG. 9 showing the center stick depict environmental structure that forms no part of the claimed design.
